UNITED STATES PATENT OFFICE.

AUGUST MERTES, OF LAKewood, OHIO.

DEVICE FOR DRILLING BRUSH BACKS LONGITUDINALLY.

Application filed March 5, 1924. Serial No. 697,164.

The objects of the invention are to provide means for drilling the long wooden backs of wire brushes longitudinally in order to connect the openings in which the loops of 5 tufts of brush wires are inserted so that locking wires or nails can be driven through the long rows of loops to retain them in place.

The difficulty of drilling such long openings in hard wood, which must, from the 10 nature of the case, be of very small diameter, is well understood, since the drills unsupported will not be able to drill the holes required with any degree of accuracy, because they will not be sufficiently rigid for 15 this purpose, owing to their extreme length.

To accomplish the desired results, the wooden back, after it has been vertically drilled to form the openings that receive the looped wires, is placed bottom up upon 20 a platform, upon which spaced guide pins are secured, that enter the socket openings for the looped wires. These pins are provided with registering openings that receive the drills and keep them in alignment with 25 the vertical openings.

The invention includes a platform, provided with rows of longitudinally and transversely spaced pins secured to its upper surface, said pins in each row being provided 30 with registering horizontal openings.

It includes opposed groups of drills, positioned to pass through the wooden brush and through the horizontal openings in the vertical guide pins, which enter the vertical 35 openings in the brush back inverted over them.

It includes two opposed sets of drills and means for revolving the drills in each set at an equal rate of speed, and means for simultaneously forcing them through the wood, and also includes automatically acting means 40 for removing the drills from the work, and a common source of power for the drills.

The advantages of the device are obvious, 45 since by its use only a few locking wires will be required to hold the wire tufts in place, and the mechanism required to drill the openings and to cut and feed the locking wires will be much simplified.

The invention is illustrated in the accompanying drawings, hereinafter more fully described and specifically pointed out in the claims.

In the accompanying drawings, Fig. 1 is 50 a side elevation of the device, showing the

mode of feeding the gangs of drills simultaneously for revolving them, and for removing them from the work.

Fig. 2 is a plan of the pin supporting plate, showing the positions of the drills. 60 Fig. 3 is a longitudinal section thereof; Fig. 4 is a bottom plan of the drill holding head; and Fig. 5 is a perspective of one of the holding pins for the brush back.

In these views, 1 represents a table in 65 which rows of vertical guide pins, 2, 2, are secured in parallel horizontal and transverse rows.

3 is the brush back, in which vertical openings, 4, 4, are bored to receive the looped 70 tufts of wire. The pins, 2, 2, are spaced to enter the openings, 3, in the brush when the brush is turned face downward over them.

The guide pins in each row are provided with aligned openings, 5, through which 75 elongated drill rods, 6, 6, pass from opposite ends of the brush back, and are guided accurately therein.

The drills are preferably arranged in gangs, which enter opposite ends of the back 80 as shown.

The drills in each gang of drills are operated by means of worm gears, 7, 7, mounted on the drill shafts, 8, 8, in a head, 9 or 9', and a worm, 10, which is operated by means 85 of a shaft, 11, and pulley, 12, and a common source of power, such as shafting, 13, and belts 14, 14.

The two heads, 9 and 9', at opposite ends of the machine are slidably movable upon a 90 base 1^a towards the ends of the brushes by means of chains or other flexible draw means, 15, 15, an intermediate windlass, 16, and crank, 17.

The crank is turned until the gangs of 95 drills nearly meet each other through the wood, and counter-weights, 18, 18, return the drills and heads to their original positions.

The brush back is then removed and 100 another put in its place.

The limit of movement of the drills is adjusted by means of a disc 19 revolvable in the head to one edge of which the chain 15 is attached at 20. A screw 23 secures the 105 disc in adjusted position.

Having described the invention, what I claim as new and desire to secure by Letters Patent is:

1. In a device for drilling in a longitudi- 110

2
nal direction a brush back, having longitudinal rows of spaced vertical openings therein, a base plate, on which said brush back rests in inverted position, rows of longitudinally and transversely spaced vertical guide pins, 5 projecting from the upper face of the base plate, the pins in each longitudinal row being provided with aligned transverse openings, a gang of drills operating at each end 10 of said base plate to pass through said transverse openings in said rows of pins, a head in which each gang of drills is revolvable, means for revolving each gang of drills, and a common source of power for said revolving 15 means.

2. In a device for drilling in a longitudinal direction a brush back, having longitudinal rows of spaced vertical openings therein, a base plate, on which said brush back rests 20 in inverted position, rows of longitudinally and transversely spaced vertical guide pins, projecting from the upper face of the base plate, the pins in each longitudinal row being provided with aligned transverse openings, 25 a gang of drills operating at each end of said base plate to pass through said transverse openings in said rows of pins, a

head in which each gang of drills is revolvable, means for revolving each gang of drills, and a common source of power, and means 30 for propelling said gangs of drills towards and from said brush back.

3. In a device for drilling in a longitudinal direction a brush back, having longitudinal rows of spaced vertical openings therein, a base plate, on which said brush back rests 35 in inverted position, rows of longitudinally and transversely spaced vertical guide pins, projecting from the upper face of the base plate, the pins in each longitudinal row being provided with aligned transverse openings, 40 a gang of drills operating at each end of said base plate to pass through said transverse openings in said rows of pins, a head 45 in which each gang of drills is revolvable, means for revolving each gang of drills, and a common source of power for said revolving means, and means for simultaneously moving said gangs of drills toward and into said brush back, and return means therefor. 50

In testimony whereof, I hereunto set my hand this 22nd day of October, 1923.

AUGUST MERTES.
